(57) **CLAIM**

The ornamental design for a backpack, as shown and described.

DESCRIPTION

FIG. 1 is a perspective view of a new design for a backpack having a plurality of compartments shown in a closed condition.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a perspective view of the backpack of FIG. 1 shown having a first compartment in an open condition.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof.

FIG. 14 is a bottom plan view thereof.

FIG. 15 is a perspective view of the backpack of FIG. 1 shown having a second compartment in an open condition.

FIG. 16 is a front elevation view thereof.

FIG. 17 is a rear elevation view thereof.

FIG. 18 is a left side elevation view thereof.

FIG. 19 is a right side elevation view thereof.

FIG. 20 is a top plan view thereof; and,

FIG. 21 is a bottom plan view thereof.

1 Claim, 21 Drawing Sheets
